(57) **CLAIM**

The ornamental design for a ceiling lift, as shown and described.

DESCRIPTION

FIG. 1 is a front view of one embodiment of the ceiling lift showing the new design;

FIG. 2 is a right side view of the ceiling lift of FIG. 1;

FIG. 3 is a rear view of the ceiling lift of FIG. 1;

FIG. 4 is a left side view of the ceiling lift of FIG. 1;

FIG. 5 is a top view of the ceiling lift of FIG. 1;

FIG. 6 is a bottom view of the ceiling lift of FIG. 1; and,

FIG. 7 is a perspective view of the ceiling lift of FIG. 1.

The portions of the Figures shown in broken lines are not part of the claimed design but are for illustration only.

1 Claim, 4 Drawing Sheets
